BY MESNE ASSIGNMENTS, TO SANFORD MILLS, OF SANFORD, MAINE, A CORPORA-
TION OF MAINE

AUTOMATIC SHUTTLE-CHANGING MECHANISM FOR DOUBLE LOOMS

Application filed October 26, 1928. Serial No. 315,170.

Our invention relates to textile looms and deals more particularly with that type in which are employed two shuttles operating simultaneously.

5 The general object of our invention is to provide means by which a shuttle containing a practically threadless bobbin may be automatically replaced by another in which is a fully-stocked bobbin,—the transfer being 10 made without interrupting the operation of the loom, and without particular attention being given the matter by the loom tender.

In a co-pending application for a patent on shuttle-changing devices, filed by us on January 27, 1928, Ser. No. 249,905, a construction is disclosed which contemplates a combined manual and automatic actuation of the parts to accomplish this purpose, but in this invention the operator of the loom requires to be 20 constantly on the watch for any empty bobbin and must start the mechanism which automatically makes the transfer of shuttles just prior to the complete depletion of the thread on the bobbin.

25 In our present invention no manual effort on the part of the loom tender is required in the operation of changing the shuttles. Instead, there is provided in each shuttle a resilient feeler making continual contact with the 30 outside layer of thread wound on the bobbin. As the thread is taken away in the process of weaving, the feeler moves inwardly, or toward the axis of the bobbin, and finally, when the bobbin has become nearly depleted 35 of thread, completes and closes an electric circuit by contacting with a metallic element in the shuttle which, with interconnecting conductors in the shuttle-box causes a magnet or solenoid included in the circuit to be 40 energized and to put into action certain parts of the apparatus which enables those immediately concerned in the shuttle changing to function.

One of the fundamental objects of our improved apparatus, which is fully automatic in its action, is to eliminate the loss of operating time which in the conventional type of loom is occasioned by frequent shut-downs to re-stock the shuttle.

50 Another object concerns the method of dis-

charging the empty shuttles from, and admitting the fully stocked ones to the shuttle-box,—the latter operation being performed by simply allowing the shuttle at the proper time to fall into its position in the shuttle-box.

And a further object resides in the safety mechanisms provided for fortifying the several portions of the apparatus against accidental injury due to the non-functioning or 60 disarrangement of any of the individual elements.

We have other objects in view and these will be set forth hereinafter, as the description of the apparatus develops, and for the 65 purpose of illustrating our invention we have prepared the accompanying drawings disclosing one and the preferred embodiment thereof.

In these drawings,—

70 Fig. 1 is a side elevation of the apparatus, the lay being shown in forward position and the shuttle-box raised;

Fig. 2 is a detail showing a fragmentary plan view of the locking mechanism;

Fig. 3 is a view in section, taken on line 3—3, Fig. 1;

Fig. 4 is a view showing a possible condition with respect to the cam actuated portion of the apparatus;

Fig. 5 is a side elevation of the apparatus with the lay shown in backward position and the shuttle-box lowered;

Fig. 6 is an end elevation of the device;

Fig. 7 is an end elevation of the shuttle-ejecting parts;

Fig. 8 is a transverse sectional view through the shuttle-box and operating parts immediately connected therewith;

Fig. 9 shows means to prevent interference 80 between the picker-heads and shuttles when the shuttle-box is lowered;

Fig. 10 is a sectional view of the lower end of the shuttle-box raising standard;

Figs. 11 and 12 are details in connection 85 with the ejecting parts;

Figs. 13 to 17 inclusive show, diagrammatically, the sequence of movements and positions of the shuttles in the operation of changing an empty for a fully stocked one; 100

Fig. 18 is a fragmentary sectional view of the shuttle and bobbin showing the resilient feeler in contact with the thread;

Fig. 19 is a fragmentary side view of the shuttle showing the insulated contact plates;

Fig. 20 is a transverse section through the shuttle, bobbin and the elements in the electric circuit;

Fig. 21 is a plan view of the shuttle separating and dropping mechanism;

Fig. 22 is an elevation of two shuttles with the separating plates interposed;

Fig. 23 is a diagrammatical outline of the loom, showing the wiring diagram for the electrically actuated shuttle release mechanism.

Figs. 24 to 28, inclusive, are diagrammatic sectional views illustrating the sequence of movements of the parts covering one cycle in the operation of ejecting an empty shuttle and placing in operative position in the apparatus a fully stocked shuttle, the sections being taken longitudinally of the shuttle boxes.

Fig. 29 is a detailed horizontal sectional view illustrating the arrangement of the shuttle ejecting slide;

Figs. 30 to 33, inclusive, are detailed views illustrating the construction of the mechanism for stopping the loom should the ejecting mechanism fail in discharging the empty shuttle from the bottom box of the three shuttle box assembly.

Figs. 34 and 35 show a plan and end view, respectively, of the mechanism employed to cut the thread, previous to the ejection of the empty shuttle.

Similar reference characters are employed to identify like parts in all views of the drawings.

In equipping a loom with our shuttle-changing device it is necessary to discard one of the original shuttle-boxes and substitute one having three compartments. The passing of the shuttles back and forth from one shuttle-box to the other is accomplished in substantially the same manner as it is in the ordinary type of loom and all movements of the new parts are timed in synchronism with the driving mechanism for the other parts of the loom.

As our apparatus is inoperative a greater portion of the time it is necessary to provide therein the proper facilities to insure coordination between the movements of the different elements, the old and the new, so that no interruption shall take place in the continuity of operation of the loom as a whole, when the time arrives for placing a fully stocked shuttle in service. In other words, the insertion of a new shuttle into the mechanism must be done in the proper sequence of loom movements.

Referring to Figs. 1, 5 and 6, 1 represents the frame of the loom, or that portion of it

on which the present apparatus is installed, 2 a part of the lay frame pivotally attached to and oscillating from the shaft 3, and 4 a spur gear secured to the shaft 5. These parts are all conventional and common to most looms of this class; and in this application it is considered necessary to describe and illustrate only those elements of the older structure which have most intimate connection with the parts included in our present invention.

On the shaft 5 is a cam 6 having two dwells or concentric peripheral surfaces of different diameters. In the operation of the loom this cam rotates continuously.

Pivoted on the pin 7 secured in a bracket on the side of the frame is a lever 8 on the upper side of which is an arm 9 carrying a roll 10. From the pin 11 hangs a link 12 connected at its lower end, at 13, with a second lever 14 which is fulcrumed on a pin 15 in a bearing 16. An extended portion of the lever 14 makes connection at 17 with the shuttle-box lifting standard 18.

Journalled on the pin 19 is a rock-shaft 20, the outer end, at 21, being connected to the rod 22, which latter extends upwardly and makes connection, at 23, with one arm of the bell-crank 24 journalled on the pin 25 in the bracket 26. The other arm of the bell-crank carries an inwardly disposed stud 27.

When no shuttles are being changed the foregoing parts, with the exception of the cam 6, remain stationary and as shown in Fig. 1, being locked by the engagement of the short arm 28 of the rock-shaft 20, with the free end of the lever 8. The spring 29 serves to hold the engaging parts in strong contact.

The picker-stick 30 is made similarly to 105 and operates in the same manner as in looms generally; the same is partly true of the picker-heads 31, but the shuttle-box 32, containing three shuttle compartments, *a*, *b* and *c*, is dissimilar.

In Fig. 8 is shown, in "up" position, a transverse sectional view of the shuttle box which is vertically movable and mounted in housings 33 supported on the lay frame structure. On its end faces are tongues which 110 operate in channels 34 in the housings and its vertical action covers a space equal to the center to center distance between two adjacent shuttle compartments. The upper end of the lifting standard 18 is secured to the 115 lower floor of the shuttle-box and serves to support the latter and control its vertical movements.

Pivoted connected to the base of the shuttle box housing is a pawl 35 which in response to the pull, at certain times, of the solenoid 36 swings downwardly sufficient to engage the stud 27 as the lay frame moves backwardly. The result of this action is 120 illustrated in Fig. 5 which shows that the

bell-crank 24 has been rotated on its pivot 25, forced the rod 22 downwardly and the arm 28 off the lever 8, permitting the latter to rise, the cam having made approximately a half revolution. But the raising of the lever 8 forces the outward end of the lever 14, at 17, down, lowering the standard 18 with the shuttle-box and bringing the latter into its "down" position, the weight of the parts together with the tension of the spring 37 effecting this result.

The shuttle-box, however, remains in this position only so long as is required for the cam to make another half revolution, the 15 larger lobe of the latter forcing the lever 8 downwardly into its former position and raising the shuttle-box again into its "up" position.

The foregoing covers one cycle of movement of the parts to lower and raise the shuttle-box.

Figs. 6 and 7 both show an end elevation of the elements employed to eject an empty shuttle,—the former illustrating the parts 25 as they are positioned before, and the latter after the shuttle has been removed from the shuttle-box.

Secured to the base of the shuttle-box housing 33 is a depending bar 38, pivoted on 30 which, at 39, is a lever 40. Extending from the upper end of this lever to which it is pivotally secured by the pin 41, is a rod 42 making connection with the ejector slide 43 by means of the pin 44.

The short arm of the lever 40 is connected by a sliding joint, at 45, to the ejector bar 46, the lower end of the latter swinging from the pin 47 and the upper end provided with a forked, swinging connection at 48 from 40 which extends the ejector arm 49.

On the standard 18 is a conical collar 50, so positioned thereon that the arm 49 abuts it on the lower, or smaller end when the shuttle-box is in "up" position which, hereinafter will be termed the "normal" position of the latter element.

Fig. 6 shows the shuttle-box in normal position and while thus disposed in the apparatus the picker stick 30 may oscillate to and fro without interference with the arm 49, or the offset portion thereof, 49'. But when the mechanism acts to transfer shuttles, the shuttle box is lowered, together with the conical collar 50 which latter forces the arm 49 outwardly so that now it rests on the larger diameter of the collar (see Figs. 11 and 12). The offset portion 49' is now in the path of the picker stick 30, engaging when it is drawn over on the forward stroke of the stick and 55 results in rearranging the other elements in the ejector mechanism, as is shown in Fig. 7. Thus in one movement forwardly the picker-stick acts to throw two operative shuttles across the lay and an empty shuttle out 60 of the mechanism.

It will be understood that the operation of changing shuttles is done very quickly, or in the time required to rotate the cam 6 one revolution. At all other times the parts of the apparatus, except for the rotation of the cam and the oscillations of the lay frame are not active and positioned as seen in Figs. 1 and 6.

If reference be had to Figs. 18, 19 and 20 the electrical arrangement used on our apparatus for energizing the solenoid 36 will be understood.

Within the shuttle is a flat spring 51, bent so that its outer portion abuts with a slight pressure on the thread T wound on the bobbin B. An L-shape offset portion 51' extends into the depression 52 made in the side of the shuttle. Also secured on the inside wall of the shuttle is a plate 53.

On the outside of the shuttle are two plates 54 and 55, the former making connection with the spring 51 and the latter with the inside plate 53. The spring and all the plates are insulated from the body of the shuttle.

In the right hand shuttle box, R, of the loom, which is the one containing two shuttle compartments, there are inserted in a side strip R' serving as a portion of the side wall of the shuttle-box, lower compartment, two plates 56 and 57 electrically insulated, and extending therefrom are wires 58 and 59 respectively. When the lower shuttle is thrown across the lay into the shuttle-box R, the respective plates make mutual contact, 95 —54 with 56 and 55 with 57, all plates being extended slightly outside of their holding elements to insure absolute contact, relatively.

In the process of operating the loom the thread is gradually drawn from the bobbin until but a comparatively few turns are left on the tapering end of the spool. The spring 51 follows the reducing diameter of the body of thread until it bears on the few turns remaining and at this point the L-shape end of the spring contacts with the plate 53 and the electrical circuit is closed, resulting in 105 energizing the solenoid 36.

Immediately the electrical circuit is closed, 115 the solenoid pulls the pawl 35 downwardly and the elements involved in the operation of lowering the three-compartment shuttle-box L are put into action,—as hereinbefore explained.

If reference be had to Figs. 13 to 17, inclusive, a comprehensive understanding of the movements of the shuttles as they pass in and out of the shuttle-boxes may be gained.

It is understood, of course, that the picker heads and the ejector slide have no vertical movement, and that the picker heads in both boxes are in respective horizontal alignment.

Assume, first, that the magazine 60 is filled 130

with fully stocked shuttles, that the shuttle-box L is in normal position, that shuttle #2 is partially stocked and shuttle #1 empty.

5 On the passing of the two shuttles, #1 and #2, from shuttle-box L to shuttle-box R, the lower of the two, shuttle #1 effects the closure of the electrical circuit which causes the pawl 35 to be depressed.

10 Before the release of these two shuttles from shuttle-box R the lay moves and the pawl engages the pin 27 which in due course moves the arm 28 off the lever 8, but the latter cannot at this point rise because the roll 10 is in contact with the larger diameter dwell α on the cam 6. During the return movement of the lay, the shuttles #1 and #2 are thrown back into the compartments from which they started, c and b , respectively.

15 On further movement of the cam the roll 10 will pass to the smaller diameter dwell y , allowing the shuttle-box L to drop into low position (see Fig. 14), remaining thus until the picker-stick 30 has moved forwardly, throwing the shuttles #2 and #3 to shuttle-box R and simultaneously causing, through the agency of the lever 40, the ejection of the empty shuttle #1 into any, convenient place, as the hopper H.

20 Immediately following the ejection of the empty shuttle #1 the high point of cam approaches the roll 10 and the shuttle box L is raised quickly to its normal or up position while the shuttles are in shuttle box R.

25 The weaving continues with the two shuttles #2 and #3 operative, until #2 is exhausted, when the procedure just outlined will be repeated,—the shuttle #2 now being ejected, as shown in Fig. 16. The loom tender's work in connection with shuttle changing is confined wholly to the duty of keeping the magazine supplied with fully stocked shuttles.

30 It will be observed that in Figs. 13 to 17 a plate 61 is shown positioned on the outside of the shuttle-box when it is in normal position and within it when in down position. The purpose of this plate is to hold back or support the upper shuttles,—as #4, #5 and #6 (see Fig. 14) at the time the two shuttles #2 and #3 are being passed to the other shuttle-box R. The actuation of this plate 61 is accomplished by mechanism shown in Figs. 6 and 21.

35 Loosely secured to the end of the stud 17 is a rod 62 which extends to the top of the lay frame where it connects with one leg of the bell-crank 63. On the opposite leg of this bell-crank a rod 64 makes connection with the pin 65, secured in the plate 61. Two pins 66 and 67 fixed in the plates are joined by the rod 68 and so positioned that they swing the plates toward each other when entering the shuttle-box, thus facilitating the entry of the plates between the pointed ends of the shuttles, as seen in Fig. 22.

To bring the plates to a definite position when swung into or out of the shuttle-box, the rod 68 may be bent near each end, as at 68', so that it abuts on the respective pivot pins 69 which, in this instance, serve as stops. And that no exact lengthwise measurement of the rod 62 may be required, a telescopic and yielding connection midway its length is provided which also serves as a safety device in case any jam occurs in the separating mechanism. The plate 61 rises and falls with the shuttle-box 32.

35 When lowering the shuttle-box L loaded with shuttles there might be an interference between the picker-heads and the pointed ends of the shuttles as the latter pass downwardly by the former, were there no provision made to prevent this occurring.

In Fig. 9 is shown an auxiliary bumper arm 70, pivotally secured to the inner end of the shuttle-box housing.

40 The picker-stick returning, abuts on the end of this bumper and receives the shock of the shuttles as they are thrown from the other shuttle-box against the picker-heads. But upon the shuttle-box L descending, the stud 71 forces the bumper away from the picker-stick which then may move further toward the end of the housing, bringing the picker-heads out of reach of the descending shuttles. A spring 70' holds the bumper in normal position, as seen in full lines, Fig. 9. Tensioning means tending to swing the picker-stick in the direction of the arrow is provided at 72 as illustrated in Fig. 7 of the drawings.

45 To provide constancy in operation of our apparatus we equip it with certain safety appliances. For instance, the standard 18 (see Fig. 10) has a bushing 72 pressed into its lower end and the solid shaft portion 18' extends therethrough, terminating in a threaded end on which is the nut 73. Intermediate the end of the bushing and the shackle 74 is a nut 75 and on each side of the bushing and abutting on one of the respective nuts is a spring 76. Thus a yielding, telescopic action is provided for in either direction which avoids breakage of parts should a jam occur in the lifting mechanism.

50 Referring to Figs. 1, 3, 4 and 5, the arm 9 has a stud 77 located directly above the roll 10. During the oscillations of the picker-stick 30 the long and short dwells, α and y , on the cam 6 are in vertical alignment with this stud as illustrated in Fig. 4 of the drawings.

55 When no shuttle-changing is taking place, and the long dwell α is in its lowermost position, the roll 10 is in adjacent relation to the latter, but when the dwell y is in its lowest position the roll is in spaced relation thereto, for the reason that the arm 8 is locked in its down position by the arm 28. Assuming that there was no stud 77 and something occurred to accidentally unlock the lever 8 while dwell y was in this low position relative to its loca-

tion on the cam, then the lever 8 could rise, out of time with the other mechanism, and precipitate a conflict between the parts due to the fact that the shuttle-box 32 would be lowered prematurely.

But by the employment of the stud 77 this condition is not present and confusion of movements of the parts impossible, even should the lever 8 be unlocked by the arm 28, 10 as in this case the stud would abut on the surface y (see Fig. 4), and hold the lever, until the picker-stick had completed its movement, in substantially the same position in which it was when locked by the arm 28.

15 In correct sequence of movements of the parts, to raise or lower the shuttle-box, the roll 10 remains always in contact with some portion of the cam face, and when the roll is contacting with the cam dwell y the stud 77 passes on the inside of the flange which, projecting from the side of the cam body serves as this shorter dwell, as seen in Fig. 5.

Before the thread on the bobbin becomes wholly depleted it must be cut or severed from 25 the body of woven material M. In Figs 34 and 35 we illustrate the device which we prefer for the accomplishment of this purpose.

On a forwardly extending portion of the frame 1 of the loom is attached a slide holder 30 78 within which operates a slide 79. Secured to the slide and offset therefrom is a cutting knife 80. A pin 81 extends through a slot in the side of the slide holder and engages the oscillatory arm 82 which is pivoted at 83 on 35 the bracket 84 fixed on the slide holder.

On the upper end of the arm 82 is an outwardly disposed stud 85, and at 86 is a spring which normally holds the slide in retracted position.

40 On the top of the shuttle-box 32 is secured a bracket with a downwardly hanging foot 87. When the shuttle-box is in normal or "up" position and swings forwardly and backwardly with the lay frame, this foot 87 clears 45 the stud 85, but when the shuttle-box is lowered and swings forwardly the foot engages the stud and causes the slide to be advanced so that it cuts the thread T extending from the bobbin in the lower shuttle. It will 50 be observed by reference to Fig. 25 that the cutting knife is shaped so that it will cut either moving forwardly or backwardly,—the intention being to do the cutting on the forward stroke, but if it misses on this movement it will be quite sure to engage the thread as it returns.

As has previously been stated, the actuation of our shuttle changing apparatus is accomplished by wholly automatic means. 60 After filling the hopper with stocked shuttles the loom tender simply throws a switch, starts his loom and gives no further thought to this particular feature in the operation of the loom,—his only care being to see that the 65 hopper is supplied with shuttles.

In Figs. 13 to 17 inclusive, are diagrammatically shown the three-shuttle box and the shuttles in the different positions they assume, incident to the passage of the latter in and out of the mechanism.

70 In Figs. 24 to 28 inclusive, we illustrate the same elements, and sequence of movements of the parts covering one cycle in the operation of ejecting an empty and placing in operative position in the apparatus of a fully stocked shuttle—the several sectional views being taken longitudinally of the shuttle boxes.

75 In Fig. 24 two operative shuttles, #1 and #2, are shown in shuttle box "R" (two-shuttle box) in position to be thrown across the lay into compartments a and b , respectively, of shuttle box "L" (three-shuttle box) by the actuation of the picker stick 30—the three-shuttle box being in "up" position.

80 Let it be assumed that shuttle #2 is partially stocked and that shuttle #1 is empty and about to be removed from the loom. The result of the movement of these two shuttles, #1 and #2, forwardly, is shown in Fig. 25. This is movement number one.

85 Next, the three-shuttle box is lowered, as seen in Fig. 26,—constituting movement number two; and following this action the lowest shuttle, #1, is ejected by the ejector slide 43 simultaneously with the movement forwardly of the two stocked shuttles, #2 and #3, from compartments b and a , respectively, into the two-shuttle box "R", as illustrated in Fig. 27 and completing movement 90 100 number three.

95 Immediately the picker sticks fall back to their original positions at the outer ends of the shuttle boxes, the three-shuttle box 32, in shuttle assembly "L", rises to its "up" or normal working position, as shown in Fig. 28, which is movement number four, leaving the shuttles and the apparatus as it was delineated in Fig. 24,—except that the magazine 60 contains one less shuttle.

100 It will be observed that on the downward movement of the three-shuttle box 32 the separating plates 61 act to support the shuttles #4, 5 and 6 so that no conflict arises between the shuttles #3 and #4 when the former is projected into the opposite shuttle box.

110 Fig. 29 is a horizontal section, or sectional plan through the lower compartment of the three-shuttle box showing particularly the ejector slide 43 which is reciprocably mounted in the shuttle box housing element 33. The slide, it will be observed, is disposed outwardly of the shuttle box 32 so as not to conflict with the latter when it is raised or lowered.

115 It might be well to state that the impact of the ejector head and likewise of the picker heads against the ends of the shuttles is of such potency that neither of the heads need 120 125 130

travel the full length of the shuttle compartments to give sufficient momentum to the shuttles to project them out of the boxes.

The ordinary two-shuttle loom is provided with facilities for protecting the working parts should a shuttle fail to throw completely across the lay from one box to the other in the operation of weaving.

This protective measure is of course retained in the loom supplied with our improvements, but we have added another safeguard which insures the prompt shut-down of the loom in case the empty shuttle does not completely clear the three-shuttle box when being ejected.

In Figs. 30 to 33 inclusive, the mechanism employed to accomplish this object is illustrated.

In the floor of shuttle compartment "c" of the three-shuttle box, is a pivotally mounted trap 88 on the under side of which is a stud 89 preferably made of some non-metallic substance or at least covered with any material insulating it from any other element with which it contacts.

On the shuttle box housing 33 are two spring arms 90 and 91 which also are insulated from the metallic portions of the loom by any suitable insulating material, as the fibre block 92. When the shuttle box is in "up" position, these spring arms are not in mutual contact.

At a convenient location on the lay frame but in contiguous relation to one of the protector fingers 93 (being one of the old elements in the loom), is a bell crank 94, pivotally mounted in the bracket 95. On the short arm, 94', of this crank a link 96 is connected and this latter extends and makes connection with the armature rod 97 of the solenoid 98.

When the three-shuttle box 32 is in "up" position and the lay frame is oscillating forwardly and backwardly, the parts are disposed as seen in Figs. 30 and 33, the protector dog or short arm 93' of the protector finger passing over the bumper block 99 (this also being an old part of the loom), and no action of the elements embodied in the safety device takes place. When the three-shuttle box is lowered, however, the stud 89 causes the two springs 90 and 91 to make mutual contact—the shuttle holding the trap 88 against upward movement in the box.

This results in closing an electrical circuit, through the wires *w* and *z*, energizing the solenoid 98 and forcing the arm 94" downwardly and the protector finger 93 forwardly. Just at this particular time the lay frame is nearly at its rearward position and the empty shuttle about to be ejected. But in the event that the ejector parts fail to discharge the shuttle completely from the box, on the forward movement of the lay frame the protector dog 93', which already is down (see

dot and dash lines, Fig. 33) engages the bumper block 99 on the main frame of the loom and forces it forwardly sufficiently to throw out the driving clutch of the loom—thereby stopping all action of the loom parts.

It will be understood that during a portion of the time in which the lay frame is moving forwardly, assuming that the three-shuttle box is in "down" position, the empty shuttle is holding the springs 90 and 91 in relative contact, with the result that the dog 93' is in readiness to act to stop the loom. But if the parts function properly and the shuttle is discharged from the box, the springs separate before the dog reaches the bumper block and the loom mechanism continues to operate without interruption.

In view of the fact that in the conventional type of two-shuttle looms a quite considerable amount of time is consumed in the operation of frequent shuttle changing, and especially when it is considered that this time is absolutely a loss in productive effort, our present invention, it is believed, will become a potent factor in reducing manufacturing costs of textiles.

What we claim and desire to secure by Letters Patent is:—

1. A loom of the class described, including a two box assembly located at one side of the loom, a three box assembly located at the other side of the loom and shiftable upwardly and downwardly to arrange an empty box above the path of the shuttles to receive a full shuttle and movable downwardly to carry the full shuttle to the shuttle path and the empty shuttle below the shuttle path to discharge the same, each of the boxes of the three box assembly having a bottom wall and the bottom walls completely separating the boxes, and means operated by the exhaustion of a shuttle while the latter is in the two box assembly to shift the three box assembly automatically.

2. A loom of the class described, including a two box assembly located at one side of the loom, a three box assembly located at the other side of the loom and shiftable upwardly and downwardly to arrange an empty box above the path of the shuttles to receive a full shuttle and movable downwardly to carry an empty shuttle below the shuttle path, each of the boxes of the three box assembly having a bottom wall and the bottom walls completely separating the boxes, means operated by an exhaustion of a shuttle while the latter is in the two box assembly for automatically moving the three box assembly downwardly, and means for automatically ejecting the empty shuttle when the three box assembly is moved downwardly.

3. A loom of the class described, including a two box assembly located at one side of the loom, a three box assembly located at the other side of the loom and shiftable upward-

ly and downwardly to arrange an empty box above the path of the shuttles to receive a full shuttle and movable downwardly to carry an empty shuttle below the shuttle path, 5 each of the boxes of the three box assembly having a bottom wall and the bottom walls completely separating the boxes, means for normally locking the shiftable assembly against upward and downward movement, 10 and means operated by the exhaustion of a shuttle while the latter is in the two box assembly to move the shiftable assembly downward.

4. A loom of the class described, including 15 a two box assembly located at one side of the loom, a three box assembly located at the other side of the loom and shiftable upwardly and downwardly to arrange an empty box above the path of the shuttles to receive a full 20 shuttle and movable downwardly to carry an empty shuttle below the shuttle path, means for normally locking the shiftable assembly against upward and downward movement, means operated by the exhaustion of a 25 shuttle while the latter is in the two box assembly to move the shiftable assembly downward, and means for automatically ejecting the empty shuttle positively from the assembly.

5. A loom of the class described, including 30 a two box assembly located at one side of the loom, a shiftable three box assembly located at the other side of the loom, means for simultaneously throwing a pair of 35 shuttles back and forth from one assembly to the other, means for locking the three box assembly, means operated by the exhaustion of a shuttle while the same is in the two box assembly for unlocking the shiftable assembly, 40 means for automatically moving the three box assembly downward when the empty shuttle is therein to carry the empty shuttle below the path of the shuttles, and means for automatically and positively ejecting the empty shuttle.

6. A loom of the class described including 45 a two box assembly located at one side of the loom, a shiftable three box assembly located at the other side of the loom, means for simultaneously throwing a pair of shuttles back and forth from one assembly to the other, means for normally locking the three box assembly against movement, means operated by the exhaustion of a shuttle while the 55 same is in the two box assembly for unlocking the shiftable assembly, means for automatically moving the shiftable assembly downward when the empty shuttle is therein to carry the empty shuttle below the path of the 60 shuttle, and means for positively ejecting the empty shuttle simultaneously with the throwing of a pair of shuttles to the two box assembly.

7. A loom of the class described, includ- 65 ing a two box assembly located at one side of

the loom, a shiftable three box assembly located at the other side of the loom, means for simultaneously throwing a pair of shuttles back and forth from one assembly to the other, means for normally locking the three box assembly against movement, means operated by the exhaustion of a shuttle while the same is in the two box assembly for unlocking the shiftable assembly, means for automatically moving the shiftable assembly downward when the empty shuttle is therein to carry the empty shuttle below the path of the shuttle, means for automatically and positively ejecting the empty shuttle simultaneously with the throwing of a pair of shuttles to the two box assembly, and means for automatically moving the shiftable assembly upwardly to carry an empty box above the path of the shuttles to receive a full shuttle.

8. A loom of the class described, including 70 a two box assembly located at one side of the loom, a shiftable three box assembly located at the other side of the loom, each of the boxes of the three box assembly having a bottom wall and the bottom walls completely separating the boxes, means for throwing a pair of shuttles back and forth from one assembly to the other, and means 75 operated by the exhaustion of a shuttle while the latter is in the two box assembly to automatically shift the three box assembly to carry the empty shuttle beyond the path of the shuttles and a full shuttle into the path of the shuttles.

9. A loom of the class described, including 80 a two box assembly located at one side of the loom, a shiftable three box assembly located at the other side of the loom, means for throwing a pair of shuttles back and forth from one assembly to the other, means operated by the exhaustion of a shuttle while the same is in the two box assembly to automatically shift the three box assembly to carry the empty shuttle beyond the path of the shuttles and a full shuttle into the path of the shuttles, and means for automatically and positively ejecting the empty shuttle while the shiftable assembly is in such position.

10. A loom of the class described, includ- 85 ing a two box assembly located at one side of the loom, a shiftable three box assembly located at the other side of the loom, means for throwing a pair of shuttles back and forth from one assembly to the other, means operated by the exhaustion of a shuttle while the latter is in the two box assembly to automatically shift the three box assembly to carry the empty shuttle beyond the path of the shuttles and a full shuttle into the path of the shuttles, means for automatically and positively ejecting the empty shuttle while the shiftable assembly is in such position, and means for automatically shifting the three 90

box assembly to carry another of its boxes beyond the shuttle path, and means for automatically feeding a full shuttle into such box.

11. A loom of the class described, including a two box assembly located at one side of the loom, a shiftable three box assembly located at the other side of the loom, means for throwing a pair of shuttles back and forth from one assembly to the other, means for normally locking the shiftable assembly against such movement, means operated by the exhaustion of a shuttle while the same is in the two box assembly for unlocking the shiftable assembly, means for moving the shiftable assembly when the empty shuttle is therein to carry the empty shuttle beyond the path of the shuttles and to carry a full shuttle into the shuttle path, and means for automatically and positively ejecting the empty shuttle.

12. A loom of the class described, including a two box assembly located at one side of the loom, a three box assembly located at the other side of the loom and having one of its boxes normally located beyond the path of the shuttles, each of the boxes of the three box assembly having a bottom wall and the bottom walls completely separating the boxes, means for throwing a pair of shuttles back and forth from one assembly to the other, means for automatically feeding a full shuttle to the said box of the three shuttle assembly, means operated by the exhaustion of a shuttle while the same is in the two-box assembly for shifting the three box assembly to carry the said full shuttle into the path of the shuttles and the empty shuttle out of the path of the shuttles, and means for automatically discharging the empty shuttle.

13. A loom of the class described, including a two box assembly located at one side of the loom, a three box assembly located at the other side of the loom and having one of its boxes normally located beyond the path of the shuttles, means for throwing a pair of shuttles back and forth from one assembly to the other, means for automatically feeding a full shuttle to the said box of the three shuttle assembly, means operated by the exhaustion of a shuttle while the same is in the two-box assembly for shifting the three box assembly to carry the said full shuttle into the path of the shuttles and the empty shuttle out of the path of the shuttles, means for discharging the empty shuttle from the three box assembly simultaneously with the movement of a pair of shuttles from the three box assembly to the two box assembly, and means for returning the three box assembly to its initial position.

14. A loom of the class described, including a two box assembly located at one side of a loom, a three box assembly located at the opposite side of the loom and shiftable upwardly and downwardly and having one of its

boxes normally located above the path of the shuttles, means for throwing a pair of shuttles back and forth from one shuttle assembly to the other, means for automatically feeding a full shuttle to the said box of the three shuttle assembly, means operated by the exhaustion of a shuttle while the same is in the two-box assembly to move the three shuttle assembly downward to carry a full shuttle into the shuttle path and the empty shuttle to a point below the shuttle path, means for positively ejecting the empty shuttle from the three shuttle assembly, and means for returning the shiftable assembly to its initial position.

15. A loom of the class described, including a two box assembly located at one side of a loom, a three box assembly located at the opposite side of the loom and shiftable upwardly and downwardly and having one of its boxes normally located above the path of the shuttles, means for throwing a pair of shuttles back and forth from one shuttle assembly to the other, means for automatically feeding a full shuttle to the said box of the three shuttle assembly, means operated by the exhaustion of a shuttle while the same is in the two-box assembly to move the three shuttle assembly downward to carry a full shuttle into the shuttle path and the empty shuttle to a point below the shuttle path, means for positively ejecting the empty shuttle simultaneously with the movement of the pair of shuttles from the three box assembly to the two box assembly, and means for returning the three box assembly to its initial position prior to the return of the pair of shuttles to the said three box assembly.

16. A device of the class described, including a two box assembly located at one side of the loom, a three box assembly located at the other side of the loom with one of its boxes arranged normally above the path of the shuttles, each of the boxes of the three box assembly having a bottom wall and the bottom walls completely separating the boxes, a hopper located above the said box in position for automatically feeding a full shuttle to the same, means for throwing a pair of shuttles back and forth from one assembly to the other, means operated by the exhaustion of a shuttle while the latter is in the two-box assembly for moving the three shuttle assembly downward to carry a full shuttle into the path of the shuttles and the empty shuttle below the path of the shuttles to discharge the latter, means for returning the three shuttle box assembly to its initial position, and automatically operated means for supporting the shuttles within the hopper while the three shuttle assembly is in its lower position.

17. A device of the class described, including a two box assembly located at one side of the loom, a three box assembly located at the other side of the loom with one of its boxes

- arranged normally above the path of the shuttles, each of the boxes of the three box assembly having a bottom wall and the bottom walls completely separating the boxes, a hopper 5 located above the said box in position for automatically feeding a full shuttle to the same, means for throwing a pair of shuttles back and forth from one assembly to the other, means operated by the exhaustion of a shuttle while the latter is in the two-box assembly for moving the three shuttle assembly downward to carry a full shuttle into the path of the shuttles and the empty shuttle below the path of the shuttles to discharge the latter, 10 means for returning the three shuttle box assembly to its initial position, a supporting device movable into and out of the hopper for supporting the shuttles within the hopper when the three box assembly is in its lowered position, and means for automatically operating the supporting device when the three box assembly is raised and lowered.
18. A device of the class described, including a two box assembly located at one side 25 of the loom, a three box assembly located at the other side of the loom with one of its boxes arranged normally above the path of the shuttles, a hopper located above the said box in position for automatically feeding a full shuttle to the same, means for throwing a pair of shuttles back and forth from one assembly to the other, means operated by the exhaustion of a shuttle while the latter is in the two box assembly for moving the three shuttle assembly downward to carry a full shuttle into the path of the shuttles and the empty shuttle below the path of the shuttles to discharge the latter, means for returning the three shuttle box assembly to its initial position, spaced shuttle supporting plates pivotally mounted on the three box assembly at the top thereof, and means for simultaneously swinging the supporting plates inwardly and outwardly when the three box assembly is raised and lowered to support the shuttles within the hopper when the three box assembly is in its lowered position.
19. A device of the class described, including a two box assembly located at one side of the loom, a three box assembly located at the other side of the loom with one of its boxes arranged normally above the path of the shuttles, a hopper located above the said box in position for automatically feeding a full shuttle to the same, means for throwing a pair of shuttles back and forth from one assembly to the other, means operated by the exhaustion of a shuttle while the latter is in the two box assembly for moving the three shuttle assembly downward to carry a full shuttle into the path of the shuttles and the empty shuttle below the path of the shuttles to discharge the latter, means for returning the three shuttle box assembly to its initial position, spaced shuttle supporting plates pivotally mounted upon the three box assembly at the top thereof and adapted to swing into and out of the hopper to support the shuttles therein when the three box assembly is in its lowered position, means for connecting the plates for causing the same to move simultaneously toward and from each other, and means for automatically actuating the plates when the said three box assembly is raised and lowered.
20. A loom of the class described, including a two box assembly located at one side of the loom, a shiftable three box assembly located at the other side of the loom and cooperating with the two box assembly and movable upwardly and downwardly to carry one shuttle box above the path of the shuttles to receive a full shuttle and another box below the path of the shuttles to discharge an empty shuttle, means for raising and lowering the three shuttle box assembly comprising a continuously rotating cam having two concentric portions of different diameters, a cam actuated lever having an arm arranged to be engaged by the cam, means for connecting the three box assembly with the said lever, locking means for holding the said lever out of engagement with the cam to hold the three box assembly normally against movement, and means operated by the exhaustion of a shuttle while the latter is in the two box assembly for moving the lever out of engagement with the cam actuated lever to permit the latter to shift the three box assembly.
21. A loom of the class described, including a two box assembly located at one side of the loom, a shiftable three box assembly located at the other side of the loom and cooperating with the two box assembly and movable upwardly and downwardly to carry one shuttle box above the path of the shuttles to receive a full shuttle and another box below the path of the shuttles to discharge an empty shuttle, means for raising and lowering the three shuttle box assembly comprising a continuously rotating cam having two concentric portions of different diameters, a cam actuated lever having an arm arranged to be engaged by the cam, a vertically movable standard supporting the three box assembly, a connecting lever pivoted between its ends and having arms connected with the standard and with the cam actuated lever, a rocking lever arranged to engage and hold the cam actuated lever out of engagement with the cam, and means operated by the exhaustion of a shuttle while the latter is in the two box assembly for moving the rocking lever out of engagement with the cam actuated lever to permit the cam to lower and raise the three box assembly.
22. A loom of the class described, including a two box assembly located at one side

- of the loom, a shiftable three box assembly located at the other side of the loom and cooperating with the two box assembly and movable upwardly and downwardly to carry one shuttle box above the path of the shuttles to receive a full shuttle and another box below the path of the shuttles to discharge an empty shuttle, means for raising and lowering the three shuttle box assembly comprising a continuously rotating cam having two concentric portions of different diameters, a cam actuated lever having an arm arranged to be engaged by the cam, a vertically movable standard supporting the three box assembly, a connecting lever pivoted between its ends and having arms connected with the standard and with the cam actuated lever, a rocking lever arranged to engage and hold the cam actuated lever out of engagement with the cam, operating means for swinging the rocking lever, and means operated by the exhaustion of a shuttle while the latter is in the two box assembly including a pawl carried by a movable portion of the loom and movable to and from a position for actuating the rocking lever operating means to permit the cam actuated lever to be engaged by the cam for lowering and raising the three box assembly.
23. A loom of the class described, including a two box assembly located at one side of the loom, a shiftable three box assembly located at the other side of the loom and cooperating with the two box assembly and movable upwardly and downwardly to carry one shuttle box above the path of the shuttles to receive a full shuttle and another box below the path of the shuttles to discharge an empty shuttle, means for raising and lowering the three shuttle box assembly comprising a continuously rotating cam having two concentric portions of different diameters, a cam actuated lever having an arm arranged to be engaged by the cam, means for connecting the three box assembly with the two box assembly with the said lever, locking means for locking the said lever out of engagement with the cam to hold the three box assembly normally against movement, means operated by the exhaustion of a shuttle while the latter is in the two box assembly for moving the lever out of engagement with the cam actuated lever to permit the latter to shift the three box assembly, and means carried by the cam actuated lever for contacting with the cam for preventing the cam actuated lever from operating should the same be unlocked out of time.
24. A loom of the class described including a two box assembly located at one side of the lay of the loom, a shiftable three box assembly located at the other side of the lay and cooperating with the two box assembly and movable upwardly and downwardly to carry one box above the shuttle path to receive a full shuttle and another below the shuttle path to discharge an empty shuttle, a reciprocating ejecting slide carried by the lay and arranged to engage the path to discharge an empty shuttle, a continuously rotating cam having concentric portions of different diameters, a cam actuated lever having means engageable with the cam for oscillating the lever, means for connecting the lever with the three box assembly for raising and lowering the same, means for locking the lever out of operating position, an operating device for the said locking means, and means operated by the exhaustion of a shuttle while the latter is in the two box assembly and including a pawl carried by the lay and movable to and from a position for actuating the operating device of the said locking means.
25. A loom of the class described including a two box assembly located at one side of the lay of the loom, a shiftable three box assembly located at the other side of the lay and cooperating with the two box assembly and movable upwardly and downwardly to carry one box above the shuttle path to receive a full shuttle and another below the shuttle path to discharge an empty shuttle, a continuously rotating cam having concentric portions of different diameters, a cam actuated lever having means engageable with the cam for oscillating the lever, means for connecting the lever with the three box assembly for raising and lowering the same, a rocking lever movable to a position for locking the cam actuated lever out of operation, an operating lever connected with the rocking lever, a pawl carried by the lay and movable to and from a position for actuating the operating lever, and means operated by the exhaustion of a shuttle while the latter is in the two box assembly for actuating the pawl.
26. A loom of the class described, including a two box assembly located at one side of the lay of the loom, a three box assembly arranged at the other side of the lay and shiftable upwardly and downwardly to arrange one box above the path of the shuttles to receive a full shuttle and another box below the path of the shuttles to discharge an empty shuttle, a reciprocating ejecting slide carried by the lay and arranged to engage the shuttle in the box below the path of travel of the shuttles when the three box assembly is lowered, and mechanism operated by the upward and downward movement of the three box assembly for reciprocating the ejecting slide.
27. A loom of the class described, including a two box assembly located at one side of the lay of the loom, a three box assembly arranged at the other side of the lay and shiftable upwardly and downwardly to arrange one box above the path of the shuttles to receive a full shuttle and another box below the path of the shuttles to discharge an empty shuttle, a reciprocating ejecting slide carried by the lay and arranged to engage the

shuttle in the box below the path of travel of the shuttles when the three box assembly is lowered, a pivoted ejecting lever, means for connecting the ejecting lever with the 5 slide, an ejecting arm carried by the lever and movable into and out of the path of the lay, and means carried by the three box assembly for moving the ejector arm into the path of the picker stick when the three box 10 assembly moves downwardly.

28. A loom of the class described, including a two box assembly located at one side of the lay of the loom, a three box assembly arranged at the other side of the lay and 15 shiftable upwardly and downwardly to arrange one box above the path of the shuttles to receive a full shuttle and another box below the path of the shuttles to discharge an empty shuttle, a reciprocating ejecting slide 20 carried by the lay and arranged to engage the shuttle in the box below the path of travel of the shuttles when the three box assembly is lowered, a pivoted ejecting lever, means for connecting the ejecting lever with 25 the slide, an ejector arm carried by the lever and movable into and out of the path of the picker stick, and a vertically movable standard carrying the three box assembly and having a tapered portion arranged to move the 30 ejecting arm into the path of the picker stick when the three box assembly moves downwardly.

29. A loom of the class described including a three box assembly located at one side of 35 the lay of the loom and movable upwardly and downwardly to arrange one of its boxes above the path of the shuttles to receive a full shuttle and another box below the path of the shuttles to discharge an empty shuttle, 40 a reciprocating ejecting slide carried by the lay and arranged to engage a shuttle in the box below the shuttle path when the assembly is moved downward, a pivoted ejecting lever, a second lever pivoted between its ends and 45 connected at one end to the ejecting lever, a link connecting the other end of the said second lever with the slide, a laterally swinging ejector arm carried by the ejector lever and movable into and out of the path of the 50 picker stick and normally maintained out of the path of the picker stick, a vertically movable standard supporting the said assembly, 55 and a cone collar mounted on the standard and arranged to move the ejector arm into the path of the picker stick when the assembly moves downwardly.

30. A loom of the class described including a three box assembly located at one side of the lay of the loom and movable upwardly and downwardly to arrange one of its boxes 60 above the path of the shuttles to receive a full shuttle and another box below the path of the shuttles to discharge an empty shuttle, a reciprocating ejecting slide carried by the lay and arranged to engage a shuttle in the box 65 below the shuttle path when the assembly is

moved downward, a pivoted ejecting lever, a second lever pivoted between its ends and connected at one end to the ejecting lever, a link connecting the other end of the said second lever with the slide, a laterally swinging ejector arm carried by the ejecting lever and movable into and out of the path of the picker stick and normally maintained out of the path of the picker stick, a vertically movable standard supporting the said assembly, 70 and a cone collar mounted on the standard and arranged to move the ejector arm into the path of the picker stick when the assembly moves downwardly. 75

31. A loom of the class described including a three box assembly located at one side of the lay of the loom and movable upwardly and downwardly to arrange one of its boxes above the path of the shuttles to receive a full shuttle and another box below the path of the shuttles to discharge an empty shuttle, a picker stick, a movable bumper carried by the lay and normally arranged to limit the backward movement of the picker stick, and means carried by the assembly and arranged to engage the bumper and move the same from its normal position when the assembly moves downward to permit the head of the picker stick to clear the shuttles during the downward and upward movement of the assembly. 80

32. A loom of the class described including a three box assembly located at one side of the lay of the loom and movable upwardly and downwardly to arrange one of its boxes above the path of the shuttles to receive a full shuttle and another box below the path of the shuttles to discharge an empty shuttle, a picker stick, a pivoted bumper carried by the lay, yieldable means for normally maintaining the bumper in position for limiting the backward movement of the picker stick, and an abutment carried by the said assembly for moving the bumper out of its normal position to permit the picker stick to move backwardly away from the shuttles during the downward and upward movement of the assembly. 100

33. A loom of the class described including a three box assembly located at one side of the lay of the loom and movable upwardly and downwardly to arrange one of its boxes above the path of the shuttles to receive a full shuttle and another box below the path of the shuttles to discharge an empty shuttle, a movable knife arranged to sever the thread of a shuttle in the box below the shuttle path, and means actuated by the lay of the loom for operating the knife when the assembly is moved downward. 115

34. A loom of the class described including a three box assembly located at one side of the lay of the loom and movable upwardly and downwardly to arrange one of its boxes above the path of the shuttles to receive a full shuttle and another box below the path 120

of the shuttles to discharge an empty shuttle, a slideable knife arranged to sever the thread of a shuttle in the box below the shuttle path when the said assembly is lowered, 5 a lever connected with and adapted to reciprocate the knife, and an abutment carried by the said assembly and normally arranged to clear the said lever during the movements of the lay and arranged to be carried by the 10 downward movement of the assembly into position for engaging the lever.

35. A loom of the class described including a three box assembly located at one side of the lay of the loom and movable upwardly and downwardly to arrange one of its boxes 15 above the path of the shuttles to receive a full shuttle and another box below the path of the shuttles to discharge an empty shuttle, ejecting mechanism for discharging an 20 empty shuttle from the box below the shuttle path, a protector finger normally arranged in an operative position, and mechanism for moving the protector finger into position for stopping the loom, comprising a circuit closing 25 device having a member mounted on the said assembly and arranged to be engaged by a shuttle in the box below the shuttle path for closing the circuit and automatically movable to open the circuit when the said 30 shuttle is discharged.

36. A loom of the class described including a three box assembly located at one side of the lay of the loom and movable upwardly and downwardly to arrange one of its boxes 35 above the path of the shuttles to receive a full shuttle and another box below the path of the shuttles to discharge an empty shuttle, ejecting mechanism for discharging an empty 40 shuttle from the box below the shuttle path, a protector finger normally arranged in an operative position, and mechanism for moving the protector finger into position for stopping the loom, comprising a circuit closing device, a member pivoted to the said assembly and arranged to extend into the shuttle box below the shuttle path and adapted to be engaged and moved outwardly by a shuttle in the said box, and spring contacts maintained closed by said member when engaged by said shuttle, said spring contacts 45 opening automatically when the shuttle is discharged and the said member relieved of pressure.

37. A loom of the class described including a three box assembly located at one side of the lay of the loom and movable upwardly and downwardly to arrange one of its boxes above the path of the shuttles to receive a full shuttle and another box below 55 the path of the shuttles to discharge an empty shuttle, ejecting mechanism for discharging an empty shuttle from the box below the shuttle path, a protector finger normally arranged in an operative position, and mechanism for moving the protector finger into 60

position for stopping the loom, comprising a circuit closing device arranged to be engaged by a shuttle in the box below the shuttle path, a solenoid in circuit with the circuit closing device, and means actuated by said solenoid for engaging the finger and moving the same to its loom stopping position. 70

38. A loom of the class described including a three box assembly located at one side of the lay of the loom and movable upwardly and downwardly to arrange one of its boxes above the path of the shuttles to receive a full shuttle and another box below the path of the shuttles to discharge an empty shuttle, ejecting mechanism for discharging an empty shuttle from the box below the shuttle path, a protector finger normally arranged in an operative position, and mechanism for moving the protector finger into position for stopping the loom, comprising a circuit closing device arranged to be engaged by a shuttle in the box below the shuttle path, a solenoid in circuit with the circuit closing device, a lever arranged to swing and move the finger to its loom stopping position, yieldable means for holding the lever out of contact with the finger, and means for connecting the lever with the solenoid whereby the lever will be actuated when the circuit is 85 closed. 90

In testimony whereof we have hereunto set our hands, this 17th day of October, 1928.

RALPH W. KNOWLTON.
HAROLD C. BENNETT.
